SPORT SHIRT COLLAR WITH FOLD-DEFINING MEANS

Ralph Adams, Macon, Ga.

Application April 5, 1952, Serial No. 280,837

3 Claims. (Cl. 2-131)

1

This invention pertains to garments having attached collars which are designed to be worn either open or closed, more especially to sport shirts or the like.

Sport shirts are distinguished from dress shirts in various particulars but more especially as to the collar construction. Since the sport shirt is designed in the expectation that the collar will usually be worn open, the collar band, which forms a customary part of the dress shirt, is omitted, the collar being attached directly to the shirt proper. However, the user of a sport shirt sometimes wishes to wear the shirt with the collar closed and with a necktie and by reason of this fact attempts have recently been made to design sport shirts for such dual use.

In a dress shirt, the neckband of the collar provides a definite fold line about which the top portion of the collar is folded but since the neckband is absent from a sport shirt collar, the fold line, when the collar is turned over, is liable to be irregular and particularly, when the collar is worn closed, the collar may be of different heights at opposite sides and may not set properly. It has heretofore been proposed to interpose a stiffener element or elements of suitable shape between the front and rear plies of the collar with the object of defining a fold line. However, the provision of such an intervening stiffener necessitates the employment of additional material; the operation of cutting this material to the proper shape; the insertion of the stiffener elements between the front and rear plies of the collar proper, and the accurate retention of these stiffener elements at the proper locations until they have been permanently fixed in place, all of which add substantially to the cost of production.

I have now discovered that the desired result may be obtained, that is to say the accurate location of a definite fold line in a sport shirt collar, in a very simple and inexpensive way and without necessitating the employment of additional parts or stiffener elements.

Thus in accordance with the present invention the provision of an accurate fold line is obtained by suitably uniting the front and rear plies of the collar proper by suitably located lines of stitches.

The attainment of this object is exemplified in the accompanying drawings wherein.

Fig. 1 is a front elevation of the upper portion of a sport shirt embodying the present invention, the collar being shown in closed position;

Fig. 2 is a similar view showing the collar in open position;

Fig. 3 is a front elevation of the collar before its attachment to the shirt body;

Fig. 4 is a section on the line 4-4 of Fig. 3, to much larger scale, and showing the fabric plies of abnormal thickness;

2

Fig. 4a is a section similar to Fig. 4 but illustrating a collar of two-ply construction; and

Fig. 5 is a view similar to Fig. 3 but showing how the fold line is related to the fold-defining means.

Referring to the drawings, the numeral 10 designates a turnover collar embodying the present invention and which is shown as attached to the shirt 11, the lower portion of the shirt being broken away. As illustrated in Fig. 4, the collar consists of three plies of textile fabric, including the front ply 12, the rear ply 13 and the lining ply 14. These three plies are all of substantially the same size and contour and except for the stitches hereinafter described comprise the entire collar. The corresponding edges of these plies are arranged in substantial registry and the upper and end edges are in-folded in accordance with usual practice in collar manufacture, as shown at 15 (Fig. 4) and are united by the sewed seam S. As here illustrated the lower edges 16 of the several plies are in registry and substantially straight and are designed to be secured directly to the body of the shirt by a seam (not shown) 20 which unites the several plies while attaching them to the shirt body. As here illustrated, the end edges 17 and 18 of the collar terminate at the front of the collar in points 17a and 18a, these end edges 17 and 18 forming the front ends of the collar when the latter is worn as shown in Figs. 1 and 2. As here illustrated, the upper corners 19 and 20 of the front flaps of the shirt body are provided with separable fasteners such as the loop 21 and button 22 by means of which the collar 25 may be held in the upright, closed position of Fig. 1.

In accordance with the present invention there is an area A (Fig. 3) of the collar (symmetrical with respect to the longitudinal center of the collar) which is bounded at its lower part by a sewed seam 23, extending parallel to the lower edges 16 of the collar plies and which terminates at the points 24 and 25 which are spaced from the adjacent end edges 17 and 18 of the collar. This area A is also bounded by an upwardly convex sewed seam 26 which intersects the seam 23 at the points 24 and 25 where the seam 26 also terminates.

Merely as an example of desirable proportions, but without specifically limiting the invention thereto, the seam 23 may be spaced from the lower edge 16 of the collar a distance approximating one-fourth the height of the collar at its central point. The central point of the curved seam 26 may be spaced from the upper edge 15 of the collar a distance approximating one-half the height of the collar at its center point, and the points 24 and 25 may be spaced from the adjacent end edges 17 and 18 of the collar a distance

approximating one-fifth the length of the lower edge 16 of the collar.

The stitches which form the seams 23 and 26 pass through all three plies of the collar, as shown in Fig. 4, and draw the front and rear plies into direct and close engagement with the liner ply 14 no other parts intervening between the liner and the front and rear plies. As thus arranged, the arched area A functions as a stiffener for the collar, and when the collar is folded, as shown in Figs. 1, 2 and 5, the fold F automatically falls along a line substantially parallel to the curved seam 26. Since the seams 23 and 26 terminate at the points 24 and 25, which are spaced from the end edges 17 and 18 of the collar, they are not visible from the front when the collar is worn and thus do not detract from the appearance of the collar.

The formation of these seams 23 and 26 at the proper location is a relatively simple matter, well within the skill of the usual operator in a shirt factory, the location of these seams being facilitated, if desired, by a simple marking of one of the plies, and since the operation does not necessitate the positioning of a separate stiffener element of less area than the front and rear ply, there is no possibility of the inaccurate placement of any of the parts due to slippage before the parts can be secured together.

Thus by this means, in a very simple and inexpensive way, an accurate fold line is provided which is found to be just as effective as though some extraneous and supplementary stiffener element were interposed between the front and rear plies.

While in the arrangement of Fig. 4 the collar is shown as comprising an interliner ply 14 of the same dimensions as the front and rear plies 12 and 13 it is possible to make a two-ply collar, as shown in Fig. 4^a embodying the same inventive concept, the only difference, as compared with the collar of Fig. 4, being that the interliner ply 14 is omitted, the stitches of the seams 23 and 26 then drawing the front and rear plies into direct contact with each other. Such a two-ply construction may be useful when the fabric employed in making the front and rear plies is unusually heavy or, on the other hand, when it is desired to make a collar which is especially soft and flexible. In any event, whether two plies or three plies are used, the provision of the area A, bounded by the straight and curved seams 23 and 26, and without including any other plies of material than those which form the collar proper, insures a definite fold line which permits the collar to be worn in the upright position of Fig. 1 with assurance that the collar will be symmetrical and of the same height at opposite sides, as well as when worn in the open position of Fig. 2.

While certain desirable embodiments of the invention have been illustrated by way of example it is to be understood that the invention is broadly inclusive of any and all modifications falling within the terms of the appended claims.

I claim:

1. A sport shirt collar devoid of neckband comprising a plurality of independent unstiffened plies of material, all of substantially the same size and contour and having their corresponding edges in registry, one at least of said plies being a front ply and another a rear ply, the upper and end edges of the several plies being infolded and being united by a sewed seam to each other, and their registering lower edges being free from each other and designed for attachment directly

to a shirt body, the several plies being coextensive in length and width and being separate from one another between the upper and lower edges except for an area defined by two lines of stitches, one comprising a substantially straight seam parallel to but spaced from the lower edge of the collar and the other line of stitches comprising an upwardly convex seam which joins the straight seam at the opposite ends of the latter, the prolongation of the convex seam line intersecting the lower edges of the collar plies at a point substantially spaced from the ends of the collar, the stitches constituting said seams passing through the several independent plies and drawing adjacent plies into direct contact with each other, the convex seam being operative to locate a line about which the collar will fold.

2. A sport shirt collar according to claim 1, wherein the straight seam is spaced from a lower edge of the collar a distance approximately one-fourth the height of the collar, the central point of the curved seam is spaced from the upper edge of the collar a distance approximately one-half the height of the collar, and each respective point at which the seams intersect is spaced from the proximate end of the collar a distance not substantially less than one-fifth the length of the lower edge of the collar.

3. A sport shirt having a collar, said collar being devoid of neckband and comprising a plurality of independent, unstiffened plies of material, said plies being coextensive in length and width and of substantially the same contour with their corresponding edges in registry, one at least of said plies being a front ply and another of said plies being a rear ply, the upper and end edges of the front and rear plies being infolded and united by a sewed seam to each other, and their registering, lower edges being directly and permanently attached to the shirt body, the several plies being separate from one another between the upper and lower edges of the collar except for an area of lenticular contour defined by two lines of stitches, one line forming a substantially straight seam parallel to but spaced from the lower edge of the collar and the other line of stitches forming an upwardly convex seam which joins the straight seam at the opposite ends of the latter, the prolongation of the convex seam line intersecting the lower edges of the collar plies at a point substantially spaced from the ends of the collar, the highest point of the convex seam being midway between the ends of the collar, the respective points of intersection of the seams being spaced from the proximate ends of the collar a distance not substantially less than one-fifth the length of the lower edge of the collar, the stitches constituting said seams passing through the independent front and rear plies and drawing adjacent plies of the collar into direct contact with each other, the convex seam being operative to locate a line about which the collar will fold.
